UNITED STATES PATENT OFFICE.

JOHN A. CADY, OF LOS ANGELES, CALIFORNIA.

GRAB FOR USE IN WELLS.

Application filed August 3, 1926. Serial No. 126,820.

This invention relates to "grabs" or fishing tools employed in the well drilling industry for removing parts which have been lost in the hole being drilled. In the drilling of 5 wells it often occurs that tools or portions thereof become lost in the hole and their presence makes further drilling difficult. The lost part must be removed, "sidetracked" or "drilled up" before the drilling 10 operation can proceed. This invention relates to tools adapted to be lowered into a well to remove members lost therein. A portion of a drill bit or a drill pipe which has been twisted off will cause serious trouble 15 at the bottom of a well and therefore much time and labor are expended in an endeavor to remove such parts from the hole.

It is an object of this invention to provide a grab whereby a lost part may be removed 20 from the hole with a minimum of time and with a minimum expenditure of labor.

In the ordinary type of grabs in use today, the lost part being grappled is not gripped until an up movement of the grab tool has 25 started. There is great possibility that a slight relative movement will occur between the grab and the part before the jaws of the grab are caused to firmly engage the part. Because of this, frequently the part will slip 30 from position between the jaws and not be engaged. This requires the grab to be reset and another attempt to catch the lost part.

It is an object of this invention to provide a grab in which the jaws thereof are caused 35 to securely engage the lost part before any up motion of the grab is commenced.

Another object of the invention is to provide a simplified form of grab in which there are no interconnected pivoted parts between 40 the tubing, by means of which the grab is pivoted to the grab members, but in which the grab members are directly connected to the tubing when moved into gripping engagement with a lost part by the drill tubing.

A still further object of the invention is to provide a grab in which washing fluid may be supplied for assisting in freeing the lost part from the bottom of the well.

Another object is to provide a grab which, after an object has been firmly gripped thereby, may be given a jar to loosen the object from the mud and permit it to be drawn to the surface.

Other objects and advantages of the invention will be made evident hereinafter.

Referring to the drawings in which I illustrate my invention:

Fig. 1 is a diagrammatic view illustrating 60 its use.

Fig. 2 is a vertical section taken through the grab showing the position of the parts when a lost part is ready to be grabbed.

Fig. 3 is a view similar to Fig. 2, but showing the parts in the positions they occupy when a lost part has been grabbed. 65

Fig. 4 is a section taken on the line 4-4 of Fig. 3.

Fig. 5 is a section taken on the line 5-5 70 of Fig. 3.

Fig. 6 is a section taken on the line 6-6 of Fig. 2.

Referring to Fig. 1, the numeral 11 represents a partly drilled well in which a lost part 12 has been lodged. This part may 75 have been lost by an uncoupling of a joint or by a twist-off or breakage of a tool. At the upper end of the well 11 is a rotary machine 13 through which a tubing 14 is extended into the well. At the lower end of 80 the tubing 14 is a grab 16 embodying the features of the invention.

Referring to Figs. 2 to 6 inclusive, the details of construction of my grab 16 will be described. The numeral 20 represents a 85 split shell which provides a cylindrical chamber 21. For the purpose of making convenient the assembling of the grab, the shell 20 is composed of two semi-cylindrical members 22. The lower ends of the members 22 are threaded as indicated at 23, and a lower collar 24 is screwed thereon, thus clamping the lower ends tightly in the position shown in the drawings. The upper ends of the members 22 are threaded as indicated at 26 and an upper collar 27 is screwed thereunto for rigidly clamping the upper ends of the members 22 together. The lower end of the tubing 14 extends through a slide bearing opening 29 formed in the 90 upper collar 27 and a bottom coupling 30 is secured to the lower end thereof, the bottom coupling being located inside the chamber 21. The grab 16 is supported at the lower end of the tubing 14 by engagement 100 of the upper collar 27 with the bottom coupling 30.

Immediately above the lower end of the shell 20 is formed an internal annular groove 33 which is formed in a horizontal plane and 110 which is substantially semi-cylindrical in cross section. An annular recess 34 is formed

in the lower part of the shell 20 above the annular groove 33. The recess 34, as illustrated in Figs. 2 and 3, is frusto-conical so that the upper end thereof is deeper than the lower end thereof.

Carried at the lower end of the shell 20 are grab members 35. In the drawings I have shown only a pair of grab members, but it should be understood that more may be provided without deviating from the invention. The grab members 35 have inner and outer arcuated faces 36 and 37. Formed on the outer faces 36 of the grab members 35 slightly above the middle are pivot lugs 38 which have semi-cylindrical faces and which rest in the annular groove 33 as shown in Figs. 2, 3 and 6. The grab members 35 are pivoted to the shell 20 by means of the pivot lugs 38 and the annular groove 33. The portions of the grab members 35 below the pivot lugs 38 constitute jaws 40 having jaw teeth 41 formed at the lower ends thereof. The jaw teeth 41 are provided with upper horizontal faces and lower diagonal faces as shown. The portions of the grab members 35 extending above the pivot lugs 38 constitute operating arms 42 and are provided with teeth 43 having upper diagonal faces and lower horizontal faces.

The grab members 35 are semi-cylindrical only in the plane of the pivot lugs 38 and therefore edge faces 44 of the grab members 35 contact in this plane. The faces 44, however, spread away from each other as the opposite ends of the grab members are approached so that the grab members are less than semi-cylindrical at all points with the exception of the portion at the plane of pivot thereof. The faces 44, where they engage, form rocking bearings and hold the grab members outward so that the pivot lugs 38 are in proper pivotal engagement in the annular groove 33. The grab members 35 are formed, as shown, so that they may pivot relative to each other and pivot relative to the shell 20. It will be seen that if the edge faces 44 were parallel and in engagement along their entire length there could be no relative pivotal movement between the grab members.

Extending inward from the inner faces 37 of the grab members 35 slightly below the pivot plane thereof are stop flanges 46 which are adapted to prevent the lost part 12 from extending upward into the grab members beyond the position in which it is shown in Fig. 3.

Positioned in the upper end of the chamber 21 of the shell 20 is an engager 49. The upper end of the engager 49 is provided with a threaded pin 50, by means of which it is connected to the bottom coupling 30 secured to the lower end of the tubing 14. The engager 49 has a body 51 which is frusto-conical, being smaller at its lower end.

The body 51 is provided with a multiplicity of annular teeth 52 which are arranged in a horizontal plane. The upper faces of the teeth 52 are horizontal, whereas the lower faces thereof are diagonal as illustrated.

Extending through an opening 54 in the engager 49 is a wash pipe 55, the lower end of the wash pipe 55 projecting a distance below the lower end of the engager 49. A stuffing box 57 is provided at the upper end of the engager 49, surrounding the wash pipe 55 for the purpose of preventing a leakage from the inside of the tubing 14 around the wash pipe 55. The upper part of the wash pipe 55 extends inside the tubing 14 and through a coupling 58 which is placed in the tubing 14 a short distance above the lower end thereof. A washer 60 is rigidly secured to the wash pipe 55 directly above the engager 49 and a loose washer 61 is placed on the top of the pipe 55 below a coupling 58. Impressed between the washers 60 and 61 is a spring 62. The spring 62 is provided for the purpose of resiliently holding the wash pipe 55 in the position shown in the drawings. If the lower end of the wash pipe 55 engages the part 12 being grappled, no injury will occur thereto, but it will be moved upward against the action of the spring 62.

The operation of the invention is substantially as follows:

The grab members 35 normally rest in the position shown in Figs. 1 and 2. The points of pivot of the grab members, as illustrated in Fig. 2, are outside the circumference of the grab members; therefore, the tendency is for the lower ends to swing outward until the center of gravity of them is below the centers of pivot. During the lowering of the grab 16, the parts are in the positions shown in Figs. 1 and 2, the grab being supported by the bottom coupling 30 which is secured to the lower end of the tubing 14.

In Fig. 2 the grab is shown lowered to the extent that the jaws 40 have surrounded the part 12. When the upper end of the part 12 which is represented by dotted lines 47 in Figs. 2 and 3 engages the stop flanges 46, the shell 20 and the grab members 35 will be stopped from movement by the tubing 14 and the engager 49 will continue to move downward, there being a relative movement between the shell and grab members and the tubing and engager. The engager 49 moves downward and passes inside the operating arms 42 of the grab members 35, spreading them outward as shown in Fig. 3. The operating arms 42 may or may not be swung into the recess 33, this depending upon the distance that they are swung outward. The engager 49 is conical and therefore easily enters between the operating arms 42. The faces of the teeth 43 and 52 are such that the engager may be lowered. The

jaws 35 move inward into the position shown in Fig. 3, so as to tightly grip the lost part 12. It should be noted that the entire weight of the tubing 14 is applied in forcing the engager 49 between the operating arms 42. This weight is sufficient to cause the jaw teeth 41 to partially imbed themselves in the outer faces of the lost part.

In order to assist in freeing the lost part, 10 washing fluid can be delivered to the upper end of the lost part through the wash tube 55. If the lower end of the wash tube 55 engages the upper end of the lost part, it will merely move upward relative to the engager and tubing without doing any damage.

After the lost part has been securely engaged, as shown in Fig. 3, the tubing 14 is raised. The horizontal faces of the teeth 43 and 52 of the operating arms and the engager respectively are in engagement and therefore the engager 49 cannot be removed from the position shown in Fig. 3. The jaw teeth 41 have upper horizontal faces, as previously explained, and therefore cannot lose their grip on the part 12. The lift on the part 12 is transferred from the tubing 14 directly through the engager 49 and the grab members 35. It is absolutely impossible for the jaw teeth 41 to lose their grip on the pipe 12 while the engager 49 is in position inside the operating arms 42 and holding them outward as shown in Fig. 3.

A very important part of the invention is 35 that the jaw teeth 41 are caused to securely grab the lost part before any upward movement of the grab 16 is started. This is desirable because of the fact that there is no danger of the part slipping from place when 40 an up movement is initiated. Another important feature of the invention is the fact that the grab members 35 are engaged by the engager 49 which is rigidly secured directly to the lower end of the tubing 14. The 45 construction of the invention is of utmost simplicity and consequently the parts may be made very rugged so as to endure great strains and have long life. The wash pipe 55 having its resilient mounting is very important to the invention since it is very 50 helpful in freeing the lost part from the bottom of the hole by washing the material away which has packed therearound.

One of the important features of my invention is that after the teeth 41 are imbedded in the surface of the lost part 12, the tubing 14 may be lowered a slight distance and then lifted suddenly causing the engager 49 to come into sudden engagement 60 with the teeth 43, thus transmitting an up-

ward jar to the lost part 12. A series of such jars is certain to loosen the lost part 12 from the mud of the well and permit it to be lifted by the grab members 35 to the surface of the ground.

65

I claim as my invention:

1. A grab comprising: a tubing; grab members; means carried at the lower end of said tubing for supporting said grab members; an engager attached directly to said tubing and being adapted to engage said grab members, thus causing them to grab a lost part, said lost part being lifted by means of said tubing, said engager, and said grab members; and a wash pipe extending from 75 said tubing through said engager and inside said grab members.

2. A grab comprising: a tubing; grab members; a shell carried at the lower end of said tubing for supporting said grab members, said shell enclosing the upper ends of said grab members; an engager attached directly to said tubing and located in said shell, said engager being adapted to engage said grab members, thus causing them to 85 grab a lost part, said lost part being lifted by means of said tubing, said engager, and said grab members; and a wash pipe extending from said tubing through said engager and inside 90 said grab members.

3. A grab comprising: a tubing; grab members; means carried at the lower end of said tubing for supporting said grab members; an engager attached directly to said tubing and being adapted to engage 95 said grab members, thus causing them to grab a lost part, said lost part being lifted by means of said tubing, said engager, and said grab members; and a resiliently mounted wash pipe extending from said tubing 100 through said engager and inside said grab members.

4. A grab comprising: a tubing; grab members; a shell carried at the lower end of said tubing for supporting said grab 105 members, said shell enclosing the upper ends of said grab members; an engager attached directly to said tubing and located in said shell, said engager being adapted to engage said grab members, thus causing them to 110 grab a lost part, said lost part being lifted by means of said tubing, said engager, and said grab members; and a resiliently mounted wash pipe extending from said tubing through said engager and inside 115 said grab members.

In testimony whereof, I have hereunto set my hand at Los Angeles, California, this 29th day of July, 1920.

JOHN A. CADY.
